PORTRABLE ELECTRIC TOOL UNIT OR THE LIKE

Walter Albert Nystrom, Arlington Heights, Ill., assignor to Skil Corporation, Chicago, Ill., a corporation of Delaware

Application June 3, 1953, Serial No. 25,305

Term of patent 14 years

(Cl. D54—14)

To all whom it may concern:

Be it known that I, Walter Albert Nystrom, a citizen of the United States, residing at Arlington Heights, in the county of Cook and State of Illinois, have invented a new, original, and ornamental Design for a Portable Electric Tool Unit or the like, of which the following is a specification, reference being had to the accompanying drawing, forming a part thereof.

In the drawing:

Fig. 1 is a view in top plan of a portable electric tool unit showing my new design.

Fig. 2 is a view in side elevation of the same.

Fig. 3 is a view in front elevation of the same.
Fig. 4 is a view in rear elevation of the same.

The dominant features of my design reside in the portions shown in full lines.

I claim:

The ornamental design for a portable electric tool unit or the like, as shown and described.

WALTER ALBERT NYSTROM.
